REVERSIBLE UNIVERSAL STRANDING AND LAYING MACHINE

William H. Simcoe, Hamden, and Michael R. Vennett, New Haven, Conn., assignors to United States Steel Corporation, a corporation of New Jersey

Application January 15, 1958, Serial No. 709,138

8 Claims. (Cl. 57—58.3)

This invention relates to a universal stranding machine and more particularly to a machine for forming wires into strands or strands into cord or rope. There are many types of strands and ropes, and in most cases separate machines are necessary for making each type of strand or rope. In some instances a few types of strand or rope may be made on the same machine. In many instances the demand for the various types of strands or ropes is such that the machines cannot be kept in operation continuously but must be idle a good percentage of the time. One type of strand is used for cutting stone. In this type of strand two or more wires are stranded together in a manner similar to that shown in the patent to De V. D'Avancourt No. 2,604,883. In such strands the wires are first stranded right lay and then left lay with a reversal section therebetween. Another type of stone sawing wire is shown in the patent to De V. D'Avancourt No. 2,003,994. In this strand a single flat wire is twisted alternately right and left lay with a reversal section between each section of right and left lay. Ordinary strands may consist of several wires stranded together either right or left lay. Rope or cord may also consist of various numbers of strands stranded together left and/or right lay. The machines of which we have knowledge all have the strands delivered from one end only of the machine and can make only a very limited number of different types of strands or ropes.

It is therefore an object of our invention to provide a stranding machine capable of making each of the types of strands, cords and ropes discussed above.

Another object is to provide a machine wherein strands or ropes can be delivered from each end of the machine.

These and other objects will be more apparent after referring to the following specification and attached drawings, in which:

Figure 1 is a plan view of the stranding machine of our invention;

Figure 2 is an enlarged elevation of the left hand end of the machine of Figure 1;

Figure 2a is an enlarged vertical sectional view of the right hand end of the machine; Figures 2 and 2a together showing the entire machine between closing dies;

Figure 3 is an enlarged sectional view showing one of the bays in more detail;

Figure 4 is an enlarged longitudinal elevation of one end portion of the machine;

Figure 5 is a plan view of the mechanism shown in Figure 4;

Figure 6 is an enlarged longitudinal elevation, partly in section, of one end of the rotor;

Figure 7 is a view looking toward the right of Figure 6;

Figure 8 is a view taken on the line VIII—VIII of Figures 2 and 2a; and

Figure 9 is a schematic view of the electrical and hydraulic systems.

Referring more particularly to the drawings, reference numeral 2 indicates the rotor of our stranding machine. As shown, this rotor consists of a center bay 4 and three

2

bays 6 on each side thereof. The center bay 4 is preferably of the tubular type consisting of a tube 8 having three cutout portions 10 around its periphery. Spiders 12 and 12' fit within the ends of tube 8 and are fastened thereto in any desired manner, such as by means of bolts. Three holes 14 are provided through the spiders 12 and 12' adjacent the outer periphery thereof for a purpose which will appear later. A hole 16 is arranged on either side of each hole 14. Hub 18 of spider 12 has an axial opening 20 therethrough and a radial opening 22 extending from the outer end of the opening 20. A sheave 24 is mounted on the hub 18 in the opening 22. A pair of rolls 26 are mounted on base 28 for rotatively supporting each of the spiders 12 and 12'. A sheave 30 is mounted on the outside of cylinder 8. An end spider 32 is provided at each end of the rotor 2. Each of the spiders 32 has a peripheral groove 34 therein for receiving flanges 36 which form part of support rollers 38 mounted on the base 28. As best shown in Figures 6 and 7 a thrust roller 40 is adjustably mounted on the base 28 and bears against the outer end of the spider 32. The spiders 32 have inwardly extending hubs 42 thereon. A trumpet 44 is fastened to the outer end of each of the spiders 32. An axial opening 46 extends through the hub 42 and trumpet 44. A standard twister head 48 is mounted on the end of the trumpet 44. This twister head has openings 50 therethrough. The number of openings varies with the number of wires being stranded. For twisting a single wire a single hole on the axis is provided, whereas when handling multiwires the openings are spaced from the axis as shown. Sheaves 52 are mounted on the trumpet 44 to act as a guide for the wire as will be explained later. Two equally spaced spiders 54 are located between the spiders 12 and 32 and between spiders 32 and 12'. The spiders 54 have hubs 56 with an axial opening 58 therethrough and a radial opening 60 communicating therewith. A guide sheave 62 is mounted on the hub 56 in the opening 60. Each spider 54 is rotatively mounted on spaced rolls 64 mounted on base 28. The spiders 12, 32 and 54 of Figure 2a are interconnected by means of three tie rods 66 and the spiders 12', 32 and 54 of Figure 2 are interconnected by three similar tie rods 66 which extend into openings 14. A spacer tube 68 surrounds each rod 66 between adjacent spiders.

A cradle 70 is mounted in each of the bays 4 and 6. Each of the cradles 70 has a shaft 72 at each end. The shafts 72 of the cradles in bays 6 are supported by means of bearings 74 mounted in the axial opening of the spiders. The left shaft 72 of the cradle in bay 4 is mounted in a support 75. A spool 76 may be mounted in each of the cradles 70 with its axis arranged transversely of the rotor 2. A die 78 is mounted on each end of the machine on the exit side of the twister head 48. A reverse lay holding sheave 80 is located adjacent each die 78 on the exit side thereof. A hauloff mechanism consisting of an idler drum 81 and driven drum 82 is mounted adjacent each sheave 80 on the exit side thereof. A takeup reel 84 is mounted on the exit side of each drum 82. A guide sheave 86 may be located above the reel 84. A counter roller 88 is located between the sheave 80 and drum 81. As best shown in Figure 8 the rotor 2 is driven from a motor 90 by means of belt 92, sheave 94, belt 96 and sheave 30. The sheave 94 is mounted on a shaft 98 together with a second sheave 100. A belt 102 drives a back shaft 104 through sheaves 100 and 106. The shaft 104 extends longitudinally of the rotor 2 to points adjacent drums 81 and 82.

A gear change mechanism 108 is connected to each end of the shaft 104. The output of each of the gear change mechanisms 108 is connected to a shaft 110 having a bevel pinion 112 at its free end. A pair of bevel

gears 114 and 116 which are splined to a shaft 118 can be selectively engaged with the pinion 112. A pinion 120 is mounted on the shaft 118 and is in mesh with a gear 122 which drives drum 82. A sprocket 124 is mounted on the shaft 118 and drives reel 84 through the usual slip drive mechanism 126. The gears 114 and 116 are connected by means of a connector 128 which slides on shaft 118. The distance between gears 114 and 116 is such that one or both gears must be out of engagement with pinion 112. The connector 128 has its other end mounted on a piston rod 130 which is connected to piston 132 of a three-position cylinder 134 having a second piston 136 therein. Air may be supplied to ports 138, 140 and 142 in cylinder 134. As shown in Figure 9 ports 138 and 140 are connected to a four-way valve 144 having two control solenoids 144S and 144S1. Port 142 is connected to a four-way valve 146 having an operating solenoid 146S. Air is supplied to the valves 144 and 146 through conduit 148. Solenoid 144S is operated by means of switch 150, solenoid 144S1 is operated by means of switch 152 and solenoid 146S by means of switch 154. Closing of switch 150 energizes solenoid 144S to move valve 144 to a position where air will be introduced into port 138, thus moving connector 128 downwardly as shown in Figure 5 so that gear 116 will be in engagement with pinion 112. Closing of switch 152 while switch 150 is open energizes solenoid 144S1 which moves valve 144 to a position where air will be entering port 140. This will move connector 128 upwardly as shown in Figure 5 so that gear 114 will be in engagement with pinion 112. Closing of switch 154 while switches 150 and 152 are open energizes solenoids 144S and 146S, thus moving valve 144 to the position where air will be delivered to port 138 and valve 146 will be moved to the position where air will enter port 142. This positions connector 128 in the position with pinion 112 being out of engagement with both gears 114 and 116.

The motor 90 is provided with the usual starter 156 which brings the motor gradually up to speed and also stops it. The starting and stopping of motor 90 may be done manually by means of a switch 158. Alternatively, the operation of starter 156 may be controlled by means of a control 160 which is connected for operation by a preset counter 162 which is connected to roll 88. The control 160 may also control the operations of switches 150, 152 and 154 by means of solenoids 150S, 152S and 154S. The takeup spool 84 is tensioned by means of a hemp rope friction brake 164.

Assuming that it is desired to make stone sawing strand consisting of a single flat wire, a spool 76 having flat wire wound thereon is placed on each of the end cradles. The wire is passed through the openings 46 and 50, die 78 and once around the sheave 80 and then around the drums 81 and 82 to the reel 84. The operator then starts the machine in operation. If the automatic control is being used, no further attention by the operator is necessary. However, the following operations may be performed manually by the operator operating switch 158 to control the motor 90. For automatic control the preset counter 162 is set to operate the control 160 at definite intervals, for example every twenty-five feet. Assuming that the rotor 2 is rotating in such a direction that the wire to the right of Figure 1 will be twisted to the right and the wire to the left will be twisted to the left, the motor 90 will operate to cause rotation in this direction until almost twenty-five feet of wire has been twisted. The motor 90 then is deenergized and its brake applied. After the motor 90 comes to a complete stop and switch 154 is closed, thus disengaging pinion 112 from gear 114. The motor 90 is then started to rotate the rotor 2 one revolution in the opposite direction. During this time the sheave 80 prevents the finished product from twisting in the die 78. The motor 90 then comes to a complete stop and the switch 150 is closed so as to engage pinion 112 with gear 116. The motor 90 is again started

to continue rotation of rotor 2 in the same direction so that the wire to the right of center as shown in Figure 1 will be twisted to the left and the wire to the left twisted right. When substantially twenty-five feet has been twisted in this manner the preset counter 162 will again cause the control 160 to operate to stop motor 90. When motor 90 comes to a complete stop the switch 154 is closed to move the pinion 112 out of engagement with gear 116 into its neutral position. The motor 90 is started in the opposite direction to rotate the rotor 2 approximately one revolution. The reversal lay holding sheave 80 will hold the finished wire from moving during this time and a reversal section is formed. Motor 90 is then stopped and the switch 152 closed to move gear 114 into mesh with pinion 112. The motor 90 is again started in operation, thus completing one cycle of operation.

If it is desired to make twisted wires of all right or all left lay, the operation is essentially the same except that there will be no reversal of lay. If only right lay or only left lay is being made the wire will be pulled from one spool only. If right lay and left lay are both being made the right lay will be pulled from one end of the machine and the left lay from the other end.

In making two-wire stone sawing strand the operation is much the same as when making a single wire strand. In this case spools 76 are placed in two of the cradles at each end of the machine. The spools will have wire wound thereon which is preferably round but which may have another shape. If the spools are in the two end bays at each end of the machine the wire from the end bay passes through the opening 46 around sheave 52 and through twister head 48. If a spool is in the second bay the wire will pass through opening 58 around sheave 62 to guide 164 mounted on spacer tube 68 and thence along the spacer tube 68 to an opening in spider 32 and down to twister head 48. As the rotor 2 rotates the spools remain substantially stationary and the two wires are twisted by the twister head 48 and formed together in die 78. In case a spool is in the first bay adjacent the center bay 4 the wire will pass through opening 58 of the spider between the first and second bay and then outwardly around sheave 62 to a guide 164 mounted on a spacer tube 68 and thence through openings in spiders 54 and 32 to the closing die 78. In making two-wire strand any of the three bays may be utilized, but it is preferred to use the first and second bays adjacent the center. In making three-wire strand spools 76 will be in each of the bays 6 and the wire will pass to the twister head 48 in the manner described above. The formed strand in each case will pass around reverse lay sheave 80, drums 81 and 82 to reel 84. The sequence of operations in making either two or three-wire strands having alternate right and left lay sections will be the same as that described above for the single wire strand. Also, in like manner all right hand lay strands may be made by one-half of the machine and all left hand lay made by the other half.

When making four to seven-wire strand the strands will be pulled from one end of the machine only. If the strand has a center wire the center wire will be usually pulled from the spool at the end bay completely through the openings 46 and 50 to the twister head 48 and the remaining wires will be pulled from the other spools through the center opening of the spider adjacent thereto and then outwardly and along the spacer tubes 68 in the manner described above.

While it is desirable to have the drive for the rotor driving the center bay 4 in order to equalize the torque of the rotor the rotor may be driven in other ways. Driving from the center bay results in a much more uniform product when pulling strands from each end of the machine.

While the description refers to the forming of wires into strands the operation is the same when forming

strands into rope or cord and the term "wire" as used in the specification and claims is meant to cover either a single wire or a plurality of wires stranded together, and the term "strand" is used to indicate the stranding of single wires or multiple wires into a stranded construction.

While one embodiment of our invention has been shown and described it will be apparent that other adaptations and modifications may be made without departing from the scope of the following claims.

We claim:

1. A stranding machine comprising a rotor, said rotor having at least two bays at each end thereof, a wire carrying spool in each of said bays, means for rotating said rotor selectively in either direction, a twister head at each end of said rotor, a closing die at the exit end of each twister head, a hauloff mechanism at the exit end of each twister head, a reel at the exit end of each twister head, means for driving said hauloff mechanisms in synchronism with the rotation of said rotor, means for disengaging said last named means, and means for causing said hauloff mechanisms to rotate in the same direction regardless of the direction of rotation of said rotor.

2. A stranding machine comprising a rotor, said rotor having at least two bays at each end thereof, a wire carrying spool in each of said bays, means for rotating said rotor selectively in either direction, a twister head at each end of said rotor, a closing die at the exit end of each twister head, a reverse lay holding sheave at the exit end of each die around which the formed strand is wrapped, means for maintaining the distance between twister heads constant, a hauloff mechanism at the exit end of each reverse lay holding sheave, a reel at the exit end of each hauloff mechanism, means for tensioning said reels, means for driving said hauloff mechanisms in synchronism with the rotation of said rotor, means for disengaging said last named means, and means for causing said hauloff mechanisms to rotate in the same direction regardless of the direction of rotation of said rotor.

3. A stranding machine comprising a rotor, said rotor having at least two bays at each end thereof, a wire carrying spool in each of said bays, means for rotating said rotor selectively in either direction, a twister head at each end of said rotor, a closing die at the exit end of each twister head, a reverse lay holding sheave at the exit end of each die around which the formed strand is wrapped, a hauloff mechanism at the exit end of each twister head, means for maintaining the distance between twister heads constant, a hauloff mechanism at the exit end of each reverse lay holding sheave, a reel at the exit end of each hauloff mechanism, means for driving said hauloff mechanisms in synchronism with the rotation of said rotor, means for disengaging said last named means, and means for causing said hauloff mechanisms to rotate in the same direction regardless of the direction of rotation of said rotor.

4. A stranding machine comprising a rotor, said rotor having a center bay and at least two bays on each side thereof, a wire carrying spool in each of said bays, means for rotating said rotor selectively in either direction, a twister head at each end of said rotor, a closing die at the exit end of each twister head, a hauloff mechanism at the exit end of each twister head, a reel at the exit end of each twister head, means for driving said hauloff mechanisms in synchronism with the rotation of said rotor, means for disengaging said last named means, and means for causing said hauloff mechanisms to rotate in

the same direction regardless of the direction of rotation of said rotor.

5. A stranding machine comprising a rotor, said rotor having a center bay and at least two bays on each side thereof, a wire carrying spool in each of said bays, the spool in the center bay being removable, means for rotating said rotor selectively in either direction, a twister head at each end of said rotor, a closing die at the exit end of each twister head, a reverse lay holding sheave at the exit end of each die around which the formed strand is wrapped, means for maintaining the distance between twister heads constant, a hauloff mechanism at the exit end of each reverse lay holding sheave, a reel at the exit end of each hauloff mechanism, means for driving said hauloff mechanisms in synchronism with the rotation of said rotor, means for disengaging said last named means, and means for causing said hauloff mechanisms to rotate in the same direction regardless of the direction of rotation of said rotor.

6. A stranding machine comprising a rotor, said rotor having a center bay and at least two bays on each side thereof, a wire carrying spool in each of said bays, the spool in the center bay being removable, means for rotating said rotor selectively in either direction, a twister head at each end of said rotor, a closing die at the exit end of each twister head, a reverse lay holding sheave at the exit end of each die around which the formed strand is wrapped, means for maintaining the distance between twister heads constant, a hauloff mechanism at the exit end of each reverse lay holding sheave, a reel at the exit end of each hauloff mechanism, means for driving said hauloff mechanisms in synchronism with the rotation of said rotor, means for disengaging said last named means, and means for causing said hauloff mechanisms to rotate in the same direction regardless of the direction of rotation of said rotor.

7. A stranding machine comprising a rotor, said rotor having at least two bays at each end thereof, a wire carrying spool in each of said bays, means for rotating said rotor selectively in either direction, a twister head at each end of said rotor, a closing die at the exit end of each twister head, a hauloff mechanism at the exit end of each twister head, means for driving said hauloff mechanisms in synchronism with the rotation of said rotor, means for disengaging said last named means, and means for causing said hauloff mechanisms to rotate in the same direction regardless of the direction of rotation of said rotor.

8. A stranding machine comprising a rotor, said rotor having a center bay and at least two bays on each side thereof, a wire carrying spool in each of said bays, means for rotating said rotor selectively in either direction, a twister head at each end of said rotor, a closing die at the exit end of each twister head, a hauloff mechanism at the exit end of each twister head, means for driving said hauloff mechanisms in synchronism with the rotation of said rotor, means for disengaging said last named means, and means for causing said hauloff mechanisms to rotate in the same direction regardless of the direction of rotation of said rotor.
